UNITED STATES PATENT OFFICE.

CHRISTOPHER D. BURTON, OF SCARBOROUGH, ENGLAND.

BOTTLE OR JAR CLOSURE.

No 826,226.

Specification of Letters Patent.

Patented July 17, 1906.

Application filed April 27, 1906. Serial No. 314,053.

To all whom it may concern.

Be it known that I, CHRISTOPHER DOVE BURTON, a subject of the King of Great Britain, residing at 1 Moorland road, in the town of Scarborough, in the county of York, England, have invented certain new and useful Improvements in Bottle or Jar Closures, of which the following is a specification.

This invention relates to improvements in bottle or jar closures, as shown in the present specification and illustrated by the accompanying drawings, that form part of the same.

The invention consists essentially, of a bottle having rounded lugs or flanges projecting from the inner wall of the neck portion, each of said lugs tapering toward one end to the extremity thereof and forming a rounded shoulder, and a stopple having a body portion adapted to be inserted in the neck of said bottle and a rim encircling said body portion at the top thereof and preferably forming part therewith and rounded flanges forming beads running in an oblique direction from the lower end thereof and tapering toward each end and disappearing into said body portion and adapted to be turned to pass over the aforesaid curved shoulders and on their uppersides engage the lower sides of the aforesaid lugs.

The objects of the invention are to eliminate all metal parts in bottle or jar closures, to provide a reliable air-tight closure readily opened or closed at the will of the user, and in this particular type of bottle to obviate the dangers incident to the chipping and grinding of glass usual to such constructions where glass parts meet.

In the drawings, Figure 1 is a perspective view of the body portion and neck of the bottle. Fig. 2 is a perspective view of the stopple to be inserted into a bottle, such as illustrated in Fig. 1. Fig. 3 is a sectional elevation of a bottle having the stopple secured therein. Fig. 4 is a side elevation of the stopple illustrated in Fig. 2. Fig. 5 is a side elevation of a slightly-modified form of stopple.

Like letters of reference indicate corresponding parts in each figure.

50 In the drawings, *a* is the body portion of the bottle, from which extends upwardly, as customary in the formation of bottles, the neck *b*.

c represents lugs or flanges, projecting laterally from the inner wall of the neck *b* of the bottle in proximity to the upper edge thereof

and arranged diametrically opposite one to the other. Each of the lugs or flanges *c* is rounded to form a bead from the interior wall of the bottle-neck, and toward one end thereof the under side inclines gradually at *d* to the upper side and disappears in the wall of the bottle, forming the rounded shoulder *e*.

f is a stopple having the body portion *g* and the rim *h* encircling said body portion at its upper end and forming part therewith. The said body portion *g* is dimensioned to be inserted into the neck *b* between said lugs *c*.

i represents flanges in the form of rounded beads projecting from the periphery of and forming part with the body portion *g* at the lower end of its sides and running in an oblique direction, each of said beads partly encircling said body portion and gradually shallowing and disappearing therein at each end in order to leave free and clear spaces between said flanges to pass the lugs *c* on the insertion of the stopple *n* in the bottle.

j is an annular groove or recess formed in the enlarged upper portion *k* of the body portion *g* and the rim *h* and having a curved bed.

l is a gasket introduced into the groove *j*, and when the stopple is in position contacting with the upper beveled edge *m* at the top of the bottle-neck. In applying this stopple to the bottle the gasket is put in place on the stopple in the groove *j*, and when the bottle has been filled with the matter or substance to be contained therein the body portion *g* of the stopple is inserted in the neck *b* of the bottle.

In order to avoid the obstructions in the form of the lugs or flanges *c*, the body portion of the stopple is inserted so that the sides of said body portion, clear of flanges, pass over said lugs or flanges *c*, and just so soon as the body portion is in to its full extent it may be then turned, which brings the upper sides of the flanges *i* in contact with the lower sides of the lugs or flanges *c*, and the more the stopple is turned the tighter in place it will be, as the upward inclination of the top sides of the flanges *i* in contact with the lower sides of the lugs or flanges *c* wedge the stopple firmly, and bringing pressure to bear on the gasket *l* the latter is squeezed in between the bed of the groove *j* and the beveled edge *m*.

In Fig. 5 a slight modification is shown in the projecting flange from the body portion, and in this figure it will be seen that the inclination of the upper side of the flange is from each end running toward the middle of

said flange—that is to say, the flange tapers from the middle to the end, thus providing a flange in which the stopple on being inserted may be turned either way and yet tighten up 5 in the similar manner, as herein described.

In this invention the salient features are the forming of the beads both on the stopple and on the neck of the bottle in order that the grinding and chipping effects in such construction will be entirely done away with. It is most essential to have the beads on the body portion of the stopple formed so, particularly at their ends, but also throughout their length, as to meet the corresponding surfaces 10 of the lugs without the passage being obstructed by any rough or sharp corners, and thus prevent the chipping or grinding of glass and the deposit of said pieces of glass into the bottle. In the present construction the pressure 15 on the gasket against the beveled surface on the neck may be brought to bear without fear of this grinding and chipping effect, as the bead from the neck at the lowermost point on its upper side meets the inclined surface of 20 the lug and passes easily over the curved shoulder to the under side of the lug, which is also rounded to correspond with the rounded surface of the bead of the stopple. Thus the fastening is secured with ease, insuring a reliable and air-tight joint. 25

What I claim as my invention is—

1. A bottle or jar closure, comprising a bottle having lugs or flanges projecting from the inner wall of the neck and forming rounded 30 beads disappearing into said interior wall at each end thereof, and a stopple having a body portion to be inserted in the neck of said bot-

tle and a rim encircling said body portion at the top thereof and forming part therewith and flanges forming rounded beads on the periphery of said body portion toward the lower end and running in an oblique direction and adapted to engage on their upper side the lower side of the aforesaid beads from the bottle-neck, as and for the purpose specified. 40

2. A bottle or jar closure, comprising a bottle having lugs or flanges forming rounded beads from the interior wall of the neck portion, said beads having their under sides incline upwardly toward one end thereof and 45 form a rounded shoulder on said under side, the said lug gradually tapering from said shoulder and disappearing in said wall, and a stopple having a body portion to be inserted in the neck of said bottle and a rim forming part therewith encircling said body portion at the top thereof and an annular groove or recess between said rim and body portion in an enlarged part of the latter, said recess having a curved bed and flanges projecting from 50 the periphery of the body portion toward the lower end thereof forming rounded beads extending in an oblique direction thereon and at each end thereof disappearing into the said body portion, and a corresponding gasket inserted in said groove or recess, as and for the purpose specified. 55

Signed at the town of Scarborough, in the county of York, England, this 9th day of April, 1906.

CHRIS. D. BURTON.
